UNITED STATES PATENT OFFICE

HENRY MARGILOFF, OF BROOKLYN, NEW YORK, ASSIGNOR TO ELSIE B. MARGILOFF, OF BROOKLYN, NEW YORK

AUTOMATIC GAS COCK CONTROL

Application filed October 13, 1930. Serial No. 488,437.

The present invention relates to safety devices for gas burners and the primary object of the invention is to provide automatic control means for closing gas cocks of gas burners should the burner become extinguished.

A further object of the invention is to provide a thermostatically controlled shut-off device for gas cocks or valves which may be readily applied to existing types of gas burners.

A further object of the invention is to provide an automatic gas cock control which will permit regulating the amount of gas supplied to the burner and is operable from any adjusted position for shutting off the flow of gas in the event heat ceases to exist at the burner.

A still further and important object of the invention is to provide a device of this character which is of extremely simple construction.

Other objects and advantages of the invention will be apparent during the course of the following detailed description, taken in connection with the accompanying drawing forming a part of this specification and in which drawing:

Figure 1 is a top plan view showing the device applied to a gas burner and with the gas cock or valve in its closed position.

Figure 2 is a section on the line 2-2 of Figure 1.

Figure 3 is an enlarged vertical section thru the gas cock.

Figures 4 and 5 are sections on the respective lines in Figure 3.

In the drawing, and wherein similar reference characters designate corresponding parts throughout the several views, the numeral 6 designates a gas burner provided with the burner feed pipe 7 which is connected by the gas cock or valve 8 to the supply pipe 9. The gas burner 6 is provided at its under side with the usual legs 10 adapted to rest upon the supporting rod 11 as in the usual manner of supporting gas burners. The stationary supporting rod 11 extends diametrically beneath the burner 6 and in the present invention serves as a mounting

for one end of the thermostatic control means 12.

The gas cock or control valve 8 is of slightly modified construction from the usual type of gas cock and embodies a valve body 13 provided with axially aligning threaded nipples 14 and 15 for respective connection with the pipes 7 and 9 and forming communication therebetween when the valve is in an open position. The valve body 13 is provided with a tapering valve seat 16 in which is rotatably mounted a tapered plug valve or cone 18 provided at its upper end with an operating handle 19. At the lower end of the valve 18 is a reduced stem portion 20 which projects below the lower end of the valve body and has threaded thereon a nut 21 against which is mounted a washer 22.

Provided in the lower end of the valve body 13 is a cavity 23 having a greater diameter than the lower end of the tapering valve seat 16. Arranged in the cavity 23 is an expansion coil spring 24 the lower end of which acts upon the washer 22 for normally urging the valve downwardly into seating engagement with the seat 16. Arranged also within the pocket or cavity 23 is a preferably flat spiral spring 25 which is extended spirally about the stem 20 inwardly of the expansion coil spring 24. This spiral spring 25 acts as a return spring for the valve 18 and has its inner end attached as at 26 to the stem 20 and has its outer end attached as at 27 to the valve body 13. A suitable stop pin 28 may be provided at the upper end of the valve plug 18 for limiting rotation of the plug thru 90°. The spiral spring 25 acts to normally rotate the valve plug to a position whereby the valve will be shut off.

The thermostatic control means 12 is adapted, when the burner is lit, to retain the gas cock or valve 8 in its opened position, and when the flame is extinguished to release the valve cock and permit automatic closing thereof by the spring 25 and thus shutting off the flow of gas to the burner.

Adapted for adjustable mounting upon the burner supporting rod 11 is a thermostat 30 which is preferably formed from two metal strips having different co-efficients of expansion.

sion. The lower ends of these thermostatic metal strips are secured together in an upward extension of a supporting sleeve 31 provided with a set screw 32 permitting adjustment of the thermostat toward and away from the burner 6. The thermostat may be slightly arcuated as shown in Figure 2 and has its upper portion arranged so as to extend into the flame of the burner when ignited.

Rigidly secured as by riveting or the like at one end to the upper end of the burner thermostat 30 is a conduction rod 34 which extends forwardly along the burner pipe 7 and has its forward end rigidly secured as by riveting or the like to the central portion of a thermostat 35 arranged at one side of the gas cock or valve 8. This rod 34 is preferably formed from a suitable metal having good thermal conductivity.

The valve thermostat 35 is also preferably formed from two metal strips having different co-efficients of expansion and the said strips are secured together at their lower ends in an extension 36 projecting from one side of the valve body 13. Affixed to, and serving to connect the upper ends of the strips of the thermostat 35 is a preferably cylindrical locking pin 38 having free sliding movement thru a guide opening 40 provided in the valve body 13 above the nipples 14 and 15 and opening into the tapering valve seat 16. The inner end of the locking pin 38 is rounded as shown in Figure 3 and is adapted for movement into any one of the series of semi-circular shaped notches 42 arranged circumferentially in the valve plug 18. These notches 42 serve as means to permit regulation of the flow of gas to the burner 6 when the burner is lit and the locking pin 38 is engaged in one of the notches. By observing Figure 3 it will be noted that when the control means 12 is in a cold condition that the locking pin 38 is out of engagement with the notches 42 so that the plug valve 18 is permitted to be returned to an off or closed position by the spring 25.

In operation, and with the parts in position as shown in the drawing, the handle 19 may be grasped for opening the valve to the desired extent against the action of the spring 25 and permitting the flow of gas from the supply pipe 9 to the burner 6. The gas escaping from the burner 6 is then ignited and the flame strikes the burner thermostat 30 heating the same and causing the thermostat to bend toward the burner and creating somewhat of a twisting action upon the rod 34. The conduction rod 34 also becomes heated and thru its thermal conductivity transmits heat to the central portion of the valve thermostat 35 so that the thermostat 35 is heated and caused to bend at its upper free end toward the valve body 13 and forcing the rounded end of the locking pin 38 into one

of the notches 42. This movement of the locking pin 38 into one of the notches 42 prevents counter-rotation of the valve plug 18 by the spring 25 and maintains an open flow of gas in the burner 6. Thus it will be seen that the locking pin 38 is moved by a twisting movement of the rod 34 and also thru heating of the thermostat 35 by the heat conducting rod 34. Attachment of one end of the rod 34 to the upper end of the thermostat 30 disposes the rod end in the flame of the burner, and by attaching the opposite end of the rod to the central portion of the thermostat 35 insures quick heating of the thermostat 35 by permitting the heat to travel in both directions from the central point of connection of the rod to the thermostat. It may be found necessary to maintain one's grip upon the handle 19 for a short period of time to permit actuating of the locking pin 38 into a locking position with the valve.

Should the flame at the burner become extinguished for any reason and heat cease to exist at the burner, the thermostats 30 and 35 will immediately move away from the burner and valve respectively so that the locking pin 38 is withdrawn from its engagement with the valve plug 18 and permits the spring 25 to rotate the valve to an off position and closing the flow of gas to the burner 6.

Thus it will be seen that an improved thermostatically controlled safety device for gas burners has been provided whereby the gas cock or valve will be automatically closed should the burner become extinguished for any reason and heat cease to exist at the burner. It will also be apparent that an extremely simple device of this character has been disclosed which may be readily applied to existing types of gas burners and one which will be quick in its action of operating the locking pin to either a holding or released relation to the valve.

Changes in detail may be made to the form of invention herein shown and described, without departing from the spirit of the invention or the scope of the following claims.

I claim:

1. In combination, a burner, a control valve for the burner including a plug valve provided with circumferentially arranged notches, means normally rotating the plug valve to a closed position, a thermostat adjacent the burner to extend into the flame thereof, a second thermostat mounted upon the control valve out of the path of the flame, a locking pin carried by the last mentioned thermostat and normally held out of engagement with said notches, and a heat conduction rod rigidly connected between the thermostats for actuating the locking pin in accordance with thermal conditions at said burner.

2. In combination, a gas burner, a con-

- trol valve for the burner including a plug valve provided with circumferential notches, means normally rotating the plug valve to an off position, a burner thermostat mounted to extend into the flame of the burner, a valve thermostat mounted at one side of the control valve, a locking pin carried by the valve thermostat for engaging in said notches, and a heat conduction rod having one end rigidly connected to the burner thermostat and its opposite end rigidly connected to the valve thermostat for movement of the locking pin.
3. In combination, a gas burner, a control valve for the burner including a plug valve provided with circumferential notches, means normally rotating the plug valve to an off position, a burner thermostat mounted to extend into the flame of the burner, a valve vent duct mounted at one side of the control valve, a locking pin carried by the valve thermostat for engaging in said notches, and a bayonet-shaped heat conduction rod rigidly connected at one end to the upper end of the burner thermostat and at its offset end rigidly connected to the central portion of the valve thermostat, said locking pin normally being out of engagement with the notches and having movement thereinto when a heat exists at the burner.
- 0 4. In thermostatic control means for gas burners, the combination of a control valve including a valve body provided with a conical valve seat, a plug valve rotatable in the valve seat and provided adjacent its upper end with a series of circumferentially spaced notches, a stem projecting from the lower end of the plug valve, a spiral spring connected between the stem and valve body for normally rotating the plug valve into an off position, said valve body having an opening therethru at said notches, a thermostat mounted at its lower end upon the valve body, a locking pin carried by the upper end of the thermostat and movable thru the opening in the valve body into said notches, a conduction rod rigidly connected at one end to the central portion of the thermostat, a second thermostat mounted to extend into the flame of the burner, and means rigidly connecting the opposite end of the conduction rod to the upper end of said second mentioned thermostat.

HENRY MARGILOFF.
